UNITED STATES PATENT OFFICE.

WILLIAM PINCKNEY FRANCIS, OF PENSACOLA, FLORIDA.

COMPOSITE BEAM STRUCTURE.

957,048.

Specification of Letters Patent.

Patented May 3, 1910.

Application filed August 21, 1909. Serial No. 513,937.

To all whom it may concern:

Be it known that I, WILLIAM PINCKNEY FRANCIS, a citizen of the United States, and a resident of Pensacola, in the county of Escambia and State of Florida, have invented a new and Improved Composite Beam Structure, of which the following is a full, clear, and exact description.

Among the principal objects which the present invention has in view are: to provide a construction wherein is combined the tensile strength of metal formation with the immobility of masonry; to provide a composite structure of metal and masonry whereby the metal members are arranged in truss form; to provide a fire-proof construction for a carrying beam; and to provide a construction which is simple, economical and efficient.

One embodiment of the present invention is disclosed in the structure illustrated in the accompanying drawings, in which like characters of reference denote corresponding parts in all the views, and in which—

Figure 1 is a perspective view of a beam and piers illustrated as partially completed and as constructed in accordance with the present invention; Fig. 2 is a side elevation partly in section, of a beam and piers, showing the construction as partially completed; Fig. 3 is a plan view of a fragment of the metal beam used by me, illustrated as resting upon a carrying beam; Fig. 4 is a cross section of a beam taken on the line 35 4—4 in Fig. 2.

The piers 7, 7 shown in the accompanying drawings are constructed in accordance with the invention for which a patent was granted to me July 16, 1907, No. 860,364, to which reference is here made. Seated upon cap plates 8, 8 thereof is a steel T-beam 9. The flanges of the T-beam 9 are rabbeted, as shown at 10, 10, to form flat surfaces to receive the first layer of bricks 11, 11 supported upon the said beam. The web 12 of the beam 9 is perforated at suitable intervals to receive the bent ends of anchor rods 13, 13. The anchor rods 13, 13 are provided with body extensions of suitable length and 50 at the upper end with hook extensions 14, 14. The web 12 is also perforated to receive the bent ends of truss rods 15, 15. The truss rods 15, 15 have vertical extensions 16, 16 in the lower end of which are bent portions which are extended through perforations in the web 12 of the T-beam 9. All

the rod and anchor members are suitably secured by screw nuts 17, 17. The truss rods 15, 15 and the anchors 13, 13 are provided in numbers to suit the demands of the various structures to which the beam is applied. The length of the anchors 13, 13 and of the vertical extensions 16, 16 is regulated by the height of the masonry designed to be superimposed upon the rabbets 10, 10 of the flanges of the beam 9.

Extended across the under face of the flanges of the beam 9 are tiles 18, 18. These are provided to protect the flanges from heat and to preserve the appearance of masonry in the completed beam. Formed in the tiles 18, 18 are metal bands 19, 19, the upper extensions 20, 20 of which are adapted to be bent over to rest upon the rabbets 1, 10 of the flanges of the beam 9.

At each end of the beam 9 there are bolted float anchors 21, 21. These anchors 21, 21 are bolted at 22, 22 to the web 12 of the beam 9.

To construct a beam formed in accordance with the present invention the operation is as follows: The metal T-beam 9 is laid across the gap between the piers 7, 7 and adjusted upon the cap plates 8, 8. The facing tiles 18, 18 are then raised into position against the surfaces of the flanges of the beam 9, and there held while the extensions 20, 20 are turned down over the rabbets 10, 10 of the said beam. If needed, temporary wooden "centers" may be used to support the tiles 18, 18 in position while the bricks of the body of the beam are being laid. The upper surface of the tiles 18, 18, where exposed, and the rabbets 10, 10, are now spread with a layer of mortar to receive the bricks 11, 11 of the lower layer of facing brick for the beam. The bricks 11, 11 are carefully laid, facing the same with the tiles 18, 18. When the walls of the beam are formed, and the filling placed in position, I prefer to float a suitable cement into the space surrounding the rods 13, 15 and 16. This cement floats intimately about the various rods constituting the anchors 13, 13 and the truss rods 15, 15 and the extensions 16, 16 in such manner that when the cement sets these metal rods are held immovably in position. The extension of the various rods and anchors is such that their tensile strength is utilized to prevent any movement on the part of the composite beam structure. Care is taken that the over-turned ends 14, 14 of the anchors

shall rest solidly upon the layer of bricks constituting the top layer, or the layer immediately adjacent thereto. This mechanical engagement of the anchors with the masonry of the beam, disposes the said anchors in such position that the tensile strength of the said anchors is utilized to hold the masonry in fixed position. When the composite beam is completed it will be found 10 that the floating anchors 21, 21 have become locked into the masonry of the piers 7, 7 as the same are raised above the cap plates 8, 8. A floor 23 is now laid, being supported by temporary wooden "centers" if desired, and 15 by permanent metal bridging structure laid between and anchored on the composite beams above described.

Having thus described my invention, what I claim as new and desire to secure by Letters Patent is:—

A composite beam structure comprising a metal beam having a central vertical extension and lateral extensions rabbeted at

the outer edge; a plurality of vertically disposed anchor rods secured to said metal beam; a plurality of truss rods secured to said metal beam between the ends thereof and having vertical extensions connected to the said beam at the ends thereof; masonry construction mounted upon said metal beam 25 to encompass the said anchor rods and truss rods to immovably hold the same; a tile facing consisting of a plurality of suitable tiles extended across the bottom of said metal beam; and metal securing devices fixedly secured in said tiles and folded over the rabbeted portions of said metal beam for holding the said tiles upon said beam.

In testimony whereof I have signed my name to this specification in the presence of 40 two subscribing witnesses.

WILLIAM PINCKNEY FRANCIS.
